(57) **CLAIM**

The ornamental design for a spinning top, as shown and described.

DESCRIPTION

FIG. 1 is a front view of the spinning top showing my new design;

FIG. 2 is a rear view thereof;

FIG. 3 is a right side view thereof;

FIG. 4 is a left side view thereof;

FIG. 5 is a top plan view thereof; and,

FIG. 6 is a bottom view thereof.

The broken lines depict the portions of the spinning top that form no part of the claimed design.

1 Claim, 3 Drawing Sheets
